UNITED STATES PATENT OFFICE.

AZEL C. HOUGH, OF SOUTH BUTLER, NEW YORK, ASSIGNOR TO THE HOUGH CASH RECORDER COMPANY, OF INDIAN ORCHARD, MASSACHUSETTS.

MANUAL SALES-RECORDER.

SPECIFICATION forming part of Letters Patent No. 618,034, dated January 17, 1899.

Application filed January 21, 1898. Serial No. 867,412. (No model.)

To all whom it may concern:

Be it known that I, AZEL C. HOUGH, of South Butler, county of Wayne, State of New York, have invented an Improvement in Manual Sales-Recorders, of which the following description, in connection with the accompanying drawings, is a specification, like letters and figures on the drawings representing like parts.

10 This invention is an improvement on the sales-recorder represented in United States Patent No. 534,795, dated February 26, 1895. That patent shows a sales-strip which is fed forward intermittently after each entry 15 thereon by or through the action of a rotating drum on which the strip is wound as it is used, said drum receiving its movement intermittently by a pawl which is actuated from the so-called "drawer-locking mechanism," which is manipulated by the salesman after each entry on the strip and preparatory to opening the drawer. In an apparatus of this kind it is a matter of great importance that each strip be thoroughly utilized and 25 that the greatest number of entries be put upon it and that the said entries be placed uniformly on the strip; but in practice by the use of the mechanism described in said patent it has been found that the movement of the drum is not uniform, and it frequently 30 happens that the strip is moved too far, due to momentum of the drum, so that a part of the strip is wasted. When the entries are widely separated, it is more difficult to foot 35 them up when the strip is removed.

One object of this invention is therefore to prevent any movement of the strip due to overrunning of the feeding movement or the action of the feeding mechanism or drum, 40 and to provide against this I have provided the recorder with a locking device under the control of the pawl for moving the drum, the said pawl the instant that it completes its forward or acting stroke moving the said locking device to positively engage and hold the 45 drum, so that it cannot move at all by momentum, and in this way the movement of the strip is always just the same distance and the entries are made uniformly close together 50 without any undue waste of paper between. The locking device shown engages a second

set of ratchet-teeth at one end of the feeding-drum.

I have also provided a novel tension device for controlling the delivery or unwinding of the strip as the roll of strip material varies in diameter. It sometimes happens that the salesman by inadvertence will start to open the drawer, forgetting to make the entry of his sales on the sales-strip, and to provide for this emergency, so that the salesman cannot open the drawer if he has not made his entry without his attention being called to the omission of making the entry, I have mounted the frame containing the slit through which the salesman makes the entry on the strip so that it may yield vertically to the pressure of the hand of the salesman in making the entry, and this pressure and depression of the frame is necessary before the drawer can be opened, 70 for the frame as it descends acts upon a lever or device which so long as the frame referred to remains in its elevated position serves to restrain the movement of the frame of the drawer-locking mechanism. The movement 75 of the drawer-locking mechanism also causes the movement of the pawl employed to rotate the drum or feeding mechanism of the strip.

Figure 1, in top view, shows a sales-recorder embodying the invention to be herein described. Fig. 2 is a sectional detail of the locking mechanism and movable bar forming a part thereof. Fig. 2^a shows in perspective the bar c⁶, which is represented in section in Fig. 2. Fig. 3 is a view of the under side of 85 the lid or top of the case. Fig. 4 is a section through the lid on the dotted line x, Fig. 3, and through the case on the dotted line x', Fig. 5. Fig. 4^a shows the latch-lever detached. Fig. 5 is a view looking down into 90 the recorder, the lid being removed, the strip used in the recorder being in position on the drum. Fig. 6 is a partial sectional enlarged detail looking at the recorder from the right of the dotted line x³, Fig. 1, the drum being 95 omitted.

The casing A, having a hinge or movable lid or top A', has an opening at its base (see Fig. 4) for the reception of a cash-drawer A², it being provided with any usual or 100 proper spaces for the reception of coins or bills, a horizontal partition A³ in the casing

covering said drawer when closed. The lid or top has an opening at A⁴, (see Fig. 4,) over which is located a movable open centered frame B, having at one end two ears b, which fit over and turn freely on a suitable rod b', sustained by ears b² of a stand b³, connected to the under side of the lid by screws b⁵, said rod forming a pivot for the frame B. The rod b' receives about it a strong spiral spring b⁴, one end of which acts against said stand and the other end against a rod b⁶, connected to and extended across the under side of the frame B, said spring acting normally with sufficient force to keep the opposite end of the said frame elevated, as shown in Fig. 4, the extent of upward movement of said frame being determined by a headed stub b⁷, depending from the free end of the frame and contacting with a suitable plate b⁸, secured to the lid.

The under side of the frame has suitable ribs b⁹, against which rest the ends of a glass or other transparent plate b¹⁰, one edge of said plate resting against lugs b¹¹, thus defining the position of said edge, it constituting one side of the entry-slot b¹², through which the salesman introduces a pencil to write upon the strip S. (Shown in Fig. 5.)

A suitable card, as b¹³, printed at its upper side and represented in Fig. 1, may be interposed between the rod b⁵ and the transparent plate.

The frame B has a downturned cross-lip, to which is connected by suitable screws b¹⁴ a spring-pressure plate b¹⁵, which bears upon the top of the strip lying on the drum C', the free end of said plate defining in this instance the upper side of the entry-slot b¹².

The strip S to receive the sales-entries is put into the machine in the form of a roll, and the end of the strip is connected in any suitable manner to the drum, and as the strip is used it is fed by and wound on the drum, the drum constituting also a table to support the strip.

The frame B has an attached hand-rest b¹⁶, held in place by screws b¹⁷.

A stand c' is secured to the under side of the lid by screws c, (see Fig. 3,) and this stand has a fulcrum c² for a lever c³, the free end of which is notched to rest against the bar c⁴, to be described, forming part of the drawer-locking means, said lever acting to lock said bar when the frame B is elevated, as represented in Fig. 6; but the salesman when making an entry through the entry-slot depresses by the weight of his hand on the plate b¹⁰, attached to said frame, the short end of the lever c³, thus lifting the opposite end of said lever from the bar c⁴, so that a pin c⁵, connected with said lever, will pass from the lowermost notch of a spring-controlled dog c⁶, pivoted at c⁷ and acted upon by a spring c⁸, and engage the notch 2 of said dog, so that said lever will be caught and held up away from the bar c⁴, so that when the finger-keys have been ma-

nipulated in the predetermined manner the said bar c⁴ may by pressure on the rod f be moved to effect the unlocking of the drawer, such movement of the bar throwing forward the pawl e, so that it, in engagement with the tooth of the series of teeth 5 of the drum, will move said drum, and in this movement of the bar c⁴ it strikes the lower end of the dog c¹ 75 and turns it about its pivot, thus removing its notch from the pin c⁵, thus leaving the long end of the lever c³ free to drop, so that it may again engage and lock the bar c⁴ in place as the latter arrives in its normal position. (Represented in Fig. 6.) The dog c¹, the stand on which it is pivoted, and the spring for normally moving said dog are substantially the same as in United States Patent No. 534,795, heretofore granted to me. If the salesman has not made his entry on the strip and attempts to open the drawer, he cannot do so, and this will at once remind him that his entry has not been made, and he will then make his entry, thus removing the locking device c⁵ from the bar c⁴. This provision provides against the carelessness of the salesman.

The platform A³ supports a metallic frame D, carrying the working parts and the shaft D' of the drum C'. The drum consists of two 95 spiders D²D³, connected with the shaft D', a tin or sheet-metal surface uniting the two spiders. The spider D² has in this instance two sets of ratchet-teeth 5 6, arranged in opposite directions, one in a circle inside the other. The teeth 5 are engaged by the push-pawl e, pivoted at e' on the bar c⁴, the shape of which is best shown in Fig. 2^a, it being pivotally mounted on studs 7 8 in arms e²e³ of a stand e⁴, secured to the interior of the casing. The bar c⁴ has a backwardly-extended arm e⁵, (see Figs. 2^a and 4,) which enters a notch in one side of a bolt e⁶, guided in an ear e⁷ and by the partition A³, the lower end of said bolt normally entering a notch 9 in the drawer A² 100 and keeping it closed against its opening-spring a¹⁰, suitably arranged behind the drawer in the case. When the bolt is lifted from the notch by the movement of the bar c⁴, the spring throws the drawer open, and the lower end of the bolt rides on the track 12 while the drawer is being opened; but when it is again closed the bolt drops by gravity, the notch in the side of the bolt being of sufficient length to permit this, but when the drawer is locked the upper side of the arm e⁵ stands close to the upper end of the notch of the bolt. The opposite end of the bar c⁴ carries a finger e⁸, which as the frame is turned in a direction to cause the pawl e to act on a tooth 5 and turn the drum one step meets one end of a dog e⁹, pivoted at e¹⁰ on a hammer-carrier e¹¹, pivoted at e¹², causing said carrier to be moved to actuate its hammer e¹³, the latter, as the finger e⁸ passes the dog e⁹ striking the gong e¹⁴ one blow, which simply indicates that the drawer has been opened. The bar c⁴ has jointed to it at 13 a push-rod f, surrounded by a spring 14, the rod being extended out

wardly through a rest f' , said rod having a suitable collar 15 and an enlarged end f^2 . The inner end of the spring 14 acts against a depending ear 16, and said spring normally acts to keep the rod f pressed to the left, Fig. 2, with the collar 15 against the rest f' . When the locking-keys 20, pivoted at 20^x and common to said patent, are moved to place the projections g' , carried thereby, all below the path of movement of the bar c^6 , then the salesman by pushing against the enlarged end f^2 throws the bar c^6 forward or toward the drum, causing the pawl e to move the drum and causing the bolt e^6 to be lifted and unlock the drawer. When the bar c^6 is moved forward by pressure on the rod f , the free end of the pawl e , attached to said bar and having its end in engagement with one of the series of teeth 5, acts to turn the drum or feeding device one step, and just as the pawl is completing its effective forward or feeding stroke a projection 42 thereon meets the arm 41 of a drum-locking device, herein shown as a three-armed lever, pivoted at h^2 , and immediately elevates the end 40 of said lever, so that it engages one of the series of teeth 6, thus instantly checking any tendency of the drum to move by momentum. As the bar c^6 and pawl e are retracted by the spring 14 on the rod f the spring 45, acting on the arm 44 of the three-armed lever h' , immediately removes the end 40 of said lever from the tooth of the series of teeth 6 just engaged by it, thus leaving the drum unlocked and the pawl e in its normal inoperative position.

The arms e^2 and e^3 support loosely a rod g , having an extended end g^x , and in case a key-lever not in the combination is operated a projection 35 of said key-lever meets an arm g^4 , adjustably connected with said rod g by a suitable set-screw g^3 , and turns said rod so that the arm g^x , connected therewith, may be turned, its free end being lowered from the position shown in Fig. 6, so that the loop or connection g^{26} , leading therefrom to the lever 36, carrying the escapement, is left free to be moved through the movement of the escapement-wheel g^9 , actuated by a normally-wound motor, thus causing the hammer e^{14} to be actuated to strike a series of sharp blows on the gong e^{15} , thereby calling attention to the drawer. The user of the recorder, having determined which particular key-levers he desires to use in the combination to effect the opening of the drawer without ringing the gong e^{15} , will loosen the set-screw g^3 and will turn the fingers g^4 on the shaft g , so that said fingers will be out of the range of movement of the pins 35 carried by those key-levers, the remaining fingers g^4 being left in their elevated position, as represented by dotted lines in Fig. 2, so that when any one of the fingers of the key-levers above it is depressed the pin 35 carried by it will strike the corresponding finger g^4 .

The key-levers, the shaft g , its fingers, the rod f , the bar c^6 , and the locking device are

substantially such as described in my former patent, No. 486,107, dated November 15, 1892.

Fig. 2 shows two of the fingers g^4 , one in full and the other in dotted lines above it.

Each key-lever 20 has co-operating with it a spring 32, which acts normally to keep the inner forked end of said key-lever elevated, with the leg 31 of the fork in contact with the rod g .

A detent h , co-operating with teeth 5, acts to prevent retrograde movement of the drum.

I believe I am the first to provide the drum or feeding mechanism for manipulating the strip of a cash-recorder with means whereby the feeding movement of the strip or of the drum may be instantly checked at the end of its predetermined stroke, thus preventing any overrunning of the feeding movement, and hence this invention is not limited to the exact device or lever shown as constituting the drum-locking mechanism. The roll or strip of paper is supported at its ends on conical pointed journals 50 and 51, the journal 50 being fixed in a stand 52, while the journal 51 is movable in a stand 53. (See Fig. 4.) The journal 51 is extended or prolonged, as shown in Fig. 5, through an elbow-lever 54, pivoted at 55, the lowermost arm of said lever being extended toward the roll of paper, where it is acted upon by a weighted latch-lever 56, pivoted at 57 on the stand 53, the lower end of said latch being notched, as shown in Fig. 4^a. The journal 51 has a shoulder 58, against which acts one end of a spiral spring 59, the opposite end of the spring resting against the lever 54, and this lever may be turned to compress the spring more or less, and consequently force the journal 51 closer and closer into the strip or roll to produce greater friction, and the lever-latch 56 will hold it in the position in which it may be put. In this way the tension on the roll of paper may be regulated so that it may be delivered to the drum undertension and avoid the formation of slack.

The partition A³ of the recorder carries a bill-file, (shown as a pin m .)

The lid A' has an opening m' , which is normally closed by a door m^2 , fixed to a pintle m^3 , having an arm m^4 , which is extended therefrom through a slot m^5 (see Fig. 3) in the lid A', so that as the door m^2 is opened said arm strikes a dog m^6 , pivoted at m^7 on a hammer-carrying lever m^8 , in turn pivoted at m^9 , and turns said lever, causing the hammer m^{10} to strike a suitable spring m^{12} or other equivalent sounding device to call attention to the fact that the door has been opened. The pivot m^9 for the lever m^8 is carried by a stand m^{13} , held in place on the lid by suitable screws, a spring m^{14} acting against the lever m^9 and a spring m^{15} acting on the dog m^6 . The opening of the door m^2 actuates the striker m^{10} ; but in closing the door the arm m^4 passes the dog m^6 and does not operate the hammer m^{10} .

The frame B has a projection or ear b^20 ,

which normally stands above the short arm of the lever c^6 .

The key-levers, the bar c^6 , and the bolt e^6 constitute what is designated in the claims as 5 the "drawer-locking mechanism."

The casing A has erected on it a table A^10 , having any usual or suitable mat, of rubber or other material, on which may be laid the money or change.

Having described my invention, what I claim as new, and desire to secure by Letters Patent, is—

1. In a sales-recorder using a continuous strip, the following instrumentalities, viz: a strip-feeding drum or device, a pawl to engage said drum and move it to feed the said strip a definite distance, a locking device controlled by said pawl and actuated thereby to immediately lock said drum or device at the end of the forward or feeding stroke of the pawl, to thereby prevent any overrunning of the feeding movement, substantially as described.

2. In a sales-recorder using a continuous strip, the following instrumentalities, viz: a strip-feeding drum or device, having at its end two sets of ratchet-teeth, the teeth of one set being pointed opposite those of the other set, a pawl to engage one set of said ratchet-teeth to move the drum or device a definite distance, and a locking device to engage a tooth of the other set of teeth to immediately lock said drum or device in place at the end of its positive or forward feeding movement, to thereby prevent any overrunning of the feeding movement, substantially as described.

3. In a sales-recorder using a continuous strip, the following instrumentalities, viz: a strip-feeding drum or device presenting two sets of ratchet-teeth, a pawl to engage one of said sets of ratchet-teeth to move said drum or device to feed the strip, a locking device composed of a lever having an end adapted 45 to engage the other set of said ratchet-teeth, said locking device being under the control of said pawl, whereby said pawl as it completes its forward or feeding stroke in actuating said drum or device, starts into action 50 to release said locking device, causing it to instantly stop any further feeding motion of said drum or device, substantially as described.

4. In a sales-recorder using a continuous strip, the following instrumentalities, viz: a strip-feeding drum or device presenting two sets of ratchet-teeth, a pawl to engage one of said sets of ratchet-teeth to move said drum or device to feed the strip, a locking device composed of a lever having an end adapted 55 to engage the other set of said ratchet-teeth, said locking device being under the control of said pawl, whereby said pawl as it completes its forward or feeding stroke in actuating said drum or device, starts into action 60 to release said locking device, causing it to in-

stantly stop any further feeding motion of said drum or device, and a spring to effect the disengagement of said locking device from the teeth with which it cooperates as 70 the feeding-pawl arrives in its normal position, substantially as described.

5. In a sales-recorder employing a continuous sales-strip, the following instrumentalities, viz: a casing, a drawer, drawer-locking 75 mechanism containing a movable bar c^6 having an attached rod by which to move it when the keys of the locking mechanism permit it, a strip-feeding drum provided with two sets of ratchet-teeth; a pawl pivoted on said bar 80 and adapted to engage one set of said teeth; means to move said pawl to actuate said drum, and a locking device normally disengaged from the other set of said ratchet-teeth but adapted to be operated by the said pawl 85 substantially at the end of its actuating stroke, to cause said locking device to act and engage a tooth of the second set of ratchet-teeth and positively check any overrunning of said drum, substantially as described. 90

6. In a sales-recorder, the following instrumentalities, viz: a case provided with a closed top or lid having an entry opening or slot through which to make an entry on a continuous sales-strip, a drum to feed said strip, 95 said drum having a series of ratchet-teeth, a pawl co-operating with one series of said teeth to move said drum intermittently to feed said strip for each new entry thereon, a locking device co-operating with the other set of teeth 100 of said drum and controlled by the said pawl to instantly engage the teeth with which it operates and stop the rotation of the drum after the same has been moved forward positively for a defined distance and the pawl for 105 so moving the drum has come to rest, thereby obviating the overrunning of the motion of the drum and the waste of sales-strip, substantially as described.

7. In a sales-recorder presenting a case provided with a top or lid having an entry-opening and containing a continuous sales-strip, the following instrumentalities, viz: a spring-supported manually-operated frame having a recording-opening, and a hand-rest; a drawer, 115 a drawer-locking mechanism containing a movable bar a lever located between the bar of said drawer-locking mechanism and said spring-supported frame, and being moved to release said bar by the depression of said frame by the hand of the salesman in making an entry on the sales-strip; a drum adapted to feed the strip, said drum being moved by a suitable pawl operatively connected to said bar; and a drum-locking mechanism adapted 125 to be thrown into operative engagement with and instantly check the motion of said drum after the pawl referred to has completed its feeding stroke, thereby preventing any overrunning of the motion of the drum and waste 130 of strip, substantially as described.

8. In a sales-recorder employing a contin-

uous strip, the following instrumentalities, viz: a drum to feed said strip; journals to receive and support the strip in roll form; a lever to move one of said journals against the end of said roll, to produce more or less friction on said roll; a spring interposed between said lever and a shoulder of said journal, and a latch to hold said lever in adjusted position, to thereby control the pressure of the journal on

said roll, and to prevent the formation of slack in the strip, substantially as described.

In testimony whereof I have signed my name to this specification in the presence of two subscribing witnesses.

AZEL C. HOUGH.
